SPINNING FRAME

Charles Morton, Providence, R. I.

Application October 28, 1931, Serial No. 571,517

8 Claims. (Cl. 19—135)

This invention relates to a spinning frame more particularly to the tensioning of the back rolls of the same, and is an improvement on my co-pending application Serial No. 531,868, filed April 5 22, 1931.

One object of this invention is to provide weights so suspended that they will not interfere with the operation of the traverse motion shaft of machines of certain types.

10 A further object of this invention is a provision of a balanced construction which will allow greater selection of means for accomplishing the desired tension on the different rolls.

A still further object of this invention is the 15 provision of a construction by which each pair of back rolls may be weighted independent of the next pair of rolls.

With these and other objects in view, the 20 invention consists of certain novel features of construction, as will be more fully described, and particularly pointed out in the appended claims.

In the accompanying drawings:

Fig. 1 is a sectional view through the spinning frames with a common weighting means extending between the back and front rolls of the units.

Fig. 2 is a section taken on line 2—2 of Fig. 1.

Fig. 3 is a top plan view of a fragmental portion of one unit of the spinning frame at substantially line 3—3 of Fig. 1, showing the connection of the hanger for the weights to the rolls.

Fig. 4 is a perspective view of the hanger for the weight for the back pairs of rolls.

In equipping spinning frames with the construction disclosed in my co-pending application above referred to, I find that in some makes of frames the traverse motion shaft is so located as to prohibit the use of weighting means such as disclosed in said application upon certain pairs of rolls, and in order to avoid the necessity of providing a different tension on these rolls and at the same time to individually weight each pair of back rolls, I have provided a yoke which may be suspended from each pair of back rolls, having arms so located as to lie in planes at either side of the front roll weight extending between the frames, and in this manner I may distribute the weight in two parts to provide a construction which will be uniform in appearance and of better balance, and one in which the traverse motion shaft will not interfere with the weights, regardless of the type of machine used; and the following is a detailed description of the present 55 embodiment of this invention illustrating the pre-

ferred means by which these advantageous results may be accomplished.

With reference to the drawings, 10 designates the base for a pair of back-to-back spinning units 11 and 12, and being identical a description of one will suffice for both.

Each unit consists of front pairs of rolls 15 and 16, intermediate pairs of rolls 17 and 18 and back pairs of rolls 19 and 20. There is also provided on each frame, braker draft rolls 21 and 22. 65 The lower rolls of each of the pairs described are suitably driven, while the upper rolls of each pair are provided in pairs with a reduced portion 23 therebetween. The front upper pair of rolls designated 15 are tensioned through a hook 24 engaging the reduced portion 23 to which a weight 26 is connected by a link 25 which weight extends across to the opposite frame and serves to tension a front pair of rolls of the opposite spinning frame unit in a similar manner. 75

The upper back rolls are similarly arranged in pairs, and I have provided a hanger or fork 27 with a hook 28 to engage the reduced portion 23 between the pairs of rolls 19. This hanger member is shaped to provide a pair of arms 29 and 30 80 and is offset to clear the lower back roll 20. The arms 29 and 30 are located in vertical planes at either side of the front roll weight 26 with links 31 and 32 extending through openings 33 and 34 in the support 10 to engage weights 35 and 36 having a laterally thin and generally rectangular cross-section and located on either side of the front roll weight 26. Each of these weights 35 and 36 extend across from one spinning unit to the other unit so as to apply tension to a pair 90 of back rolls on each of the units.

The arms 29 and 30 are provided with hooks 37 to engage the eyes 38 of each of the links to which they are connected, so that if it is desired to remove a back roll from position it is merely 95 necessary to unhook the eye 38 from the hanger hook 37 and permit the weight to be lowered and the hanger 27 lifted from the back roll. In order that the weight may be supported during removal of the back roll and thus avoid the necessity of threading the link 31 or 32 through its opening in the base 10, I provide a washer 40 of a sufficient area to prevent passage of the eye 38 through the opening in the base board, which in turn limits the movement of the link 31 or 32 100 and retains the eye in a position from which it may be readily lifted to again engage the hook 37 in replacing the parts in operative relation.

By this arrangement the structure retains all 110 of the advantages as set forth in my co-pending

application above referred to, and it additionally provides for individually weighting each pair of upper back rolls and a structure which will not interfere with the traverse motion shaft in any 5 of the usual types of machines.

5. The foregoing description is directed solely towards the construction illustrated, but I desire it to be understood that I reserve the privilege of resorting to all the mechanical changes to which 10 the device is susceptible, the invention being defined and limited only by the terms of the appended claims.

I claim:

1. In a spinning frame, groups of aligned front, intermediate and back pairs of draft rolls, independent means below said frame for weighting the upper rolls of each front pair of rolls, a hanger suspended from an upper pair of back rolls having arms straddling the front weighting means, 20 and weights secured to the arms for weighting said back rolls.

2. In combination a pair of spinning units, each having groups of aligned front, intermediate and back pairs of draft rolls, common weighting means for applying pressure to the upper rolls of a pair of front rolls on each spinning unit, and a fork suspended from one pair of upper back rolls on each frame and a pair of common weights extending between the members of each frame for 30 weighting said back rolls.

3. In combination a pair of spinning units, each having groups of aligned front, intermediate and back pairs of draft rolls, common weighting means for applying pressure to the upper rolls of a pair of front rolls on each spinning unit, and a fork suspended from one pair of upper back rolls on each frame and a pair of common weights extending between the members of each frame for 35 weighting said back rolls, said weights being located on opposite sides of the front roll weighting means.

4. In combination a pair of spinning units positioned back to back, each having pairs of front and back draft rolls, weights for applying 45 pressure to said draft rolls, one weight being common to one pair of front rolls in each unit, a member suspended from a pair of back draft

rolls in each unit, a pair of weights suspended from said members for weighting said back rolls, said weights being located on opposite sides of the common weight.

5. In combination, a pair of spinning units 80 positioned back to back, each having pairs of front and back draft rolls, weights extending from one unit to the other, one weight being common to one pair of front draft rolls in each spinning unit, and a member suspended from each pair of back draft rolls on each frame and a pair of common weights suspended from said members for weighting said back draft rolls, said weights being located on opposite sides of the common weight.

6. In a spinning machine, a pair of spinning units positioned back to back, each having pairs of front and back draft rolls, separate weights extending from one unit to the other, one weight being common to one pair of draft rolls in each unit and the other weights being common to another pair of draft rolls in each unit, said last mentioned weights being located on opposite sides of the single weight.

7. In combination, a pair of spinning units 100 positioned back to back, each having pairs of front and back draft rolls, weights for applying pressure to said draft rolls, a weight being common to one pair of front rolls in each unit, means common to the two units and independent of the front weighting means for weighting the upper roll of said back pair of draft rolls and located on opposite sides of the weight for said front rolls.

8. In combination, a pair of spinning units 110 positioned back to back, each having pairs of front and back draft rolls, weights for applying pressure to said draft rolls, a weight being common to one pair of front rolls in each unit, means common to the two units and independent of the front weighting means for weighting the upper roll of said back pair of draft rolls and located on opposite sides of the weight for said front rolls, said common weights being located in the same horizontal plane.
